UNITED STATES PATENT OFFICE

162,949

SIFTING CONTAINER

Catherine C. B. Gowland, Narberth, Pa.

Application April 12, 1948, Serial No. 145,660

Term of patent 14 years

(Cl. D44—22)

To all whom it may concern:

Be it known that I Catherine C. B. Gowland, a citizen of the United States of America residing at Narberth, Pennsylvania, have invented a new, original, and ornamental Design for a Sifting Container, of which the following is a specification, reference being had to the accompanying drawing, constituting a part hereof:

Fig. 1 is a side elevational view of a sifting container showing my new design;

Fig. 2 is a plan view; and

Fig. 3 is a perspective view of the same.

I claim:

The ornamental design for a sifting container, substantially as shown.

CATHERINE C. B. GOWLAND.
